UNITED STATES PATENT OFFICE

MILES H. GALLAGHER, OF CHICAGO, ILLINOIS

MANICURING DEVICE

Application filed November 6, 1929, Serial No. 405,222. Renewed August 25, 1932.

My invention relates in general to manicuring devices, and the object of the invention, briefly stated, is the production of an improved device of this character which is 5 rapid in operation, safe to use, and inexpensive to manufacture.

The construction of the device and its advantages will be pointed out hereinafter with reference to the accompanying drawing, in 10 which—

Fig. 1 is a side view of the device assembled on an ordinary dentists' hand piece or drill chuck;

Fig. 2 is an end view of the same;

Fig. 3 is a bottom view of the device, detached from the hand piece; while

Fig. 4 is a perspective view illustrating how the device is used.

Referring to the drawing, the reference 20 character 2 indicates a guard of the form shown, made preferably of sheet metal and nickel plated or otherwise made proof against rust, as are the other parts of the device. The guard 2 is attached to a rod 3 of 25 heavy wire which has a number of laterally extending coils 4, which slip tightly over the hand piece 6, thereby supporting the guard in position.

The reference character 5 indicates a shaft 30 or mandrel similar to those used by dentists for driving grinding tools. It extends through an opening in the guard 2. Inside the guard, the buffer wheel 7 and the steel grinding disc 8 are secured to the mandrel 35 in a manner similar to the way in which dentists' grinding tools are secured, being clamped between the cone shaped end 9 of the mandrel and the head of screw 10. The screw 10 engages a threaded hole in the end 40 of the mandrel.

It will be observed that the guard 2 is cut away on the lower side which not only exposes the buffer wheel for use but also permits the buffer wheel and grinding disc to 45 be changed without detaching the guard. There is an opening in the outside of the guard opposite the screw 10 through which the latter can be reached with a screw driver.

Access to the grinding disc 8 is obtained 50 through two finger nail openings 11 and 12,

seen in Fig. 2. These openings are preferably made with different curvatures to adapt the device for use on both large and small finger nails. One opening is also preferably spaced farther from the center than the other so as to utilize a different portion of the grinding surface of the disc 8.

The reference character 13 indicates a projection at the end of the guard, which may be formed by an upsetting operation. This projection is suitable for use as a means of pressing back the cuticle.

The operation of the device will, no doubt, be sufficiently apparent from what has been said, but may be briefly explained nevertheless. The operator will hold the device in one hand by means of the hand piece and will grasp one finger of the customer in the other hand. The motor may then be started by means of the usual foot pedal, thus rotating the buffer wheel and grinding disc. The device is then brought into position against the end of the finger, the finger nail projecting through one of the openings 11 or 12 in contact with the grinding disc 8, as shown clearly in Fig. 4. Then by suitable manipulation of the device the finger nail is rapidly shaped up as desired. After a nail has been trimmed in the proper manner it may be finished by polishing with the buffer.

It will be seen that I have produced a highly efficient manicuring device, which has numerous advantages. The abrasive surface of the disc 8 cuts very fast, and thus a finger nail may be trimmed very much more rapidly than in the case when the ordinary file is used. At the same time the rapidly rotating disc, which might be more or less dangerous otherwise, is rendered entirely safe by the guard in which it is substantially enclosed. It will be observed also that the combination of the grinding or cutting element with the buffing or polishing element makes a very efficient device, combining in one tool all the principal functions which a device of this character is required to perform. From the mechanical standpoint also the combination is very effective. The buffer wheel, being quite substantial, serves as a support for the rather flexible grinding disc 190

and renders it possible to use the latter as pointed out, while the disc does duty as a washer under the head of screw 10 for securing the buffer wheel to the mandrel, thus 5 making for a maximum simplicity.

It will be understood that although I have shown my improved manicuring device in the form of an attachment for use in connection with a dental appliance, the invention 10 is not necessarily limited to this particular embodiment, as it may be desirable, and will no doubt be cheaper where the entire apparatus is furnished, to construct the device as a manicuring tool without reference to the 15 possibility of using any part of it as a dental appliance. That is to say, it may be preferable to provide a simpler form of hand piece to which the guard may be permanently attached, with the mandrel more or less per- 20 manently connected with the flexible shaft. This eliminates the expensive drill chuck which in fact is unnecessary when the device is used solely for manicuring purposes.

Having described my invention, what I 25 consider to be new and desire to have protected by Letters Patent will be pointed out in the appended claims.

What is claimed is:

1. A manicuring device comprising a hand 30 piece, a buffer wheel and a grinding disc rotated by the shaft terminating in said hand piece, said buffer wheel serving as a support to prevent lateral bending of said disc, and a guard substantially enclosing said 35 wheel and disc but having openings through which the same may be applied to a finger nail.

2. In a manicuring device, a disc having a 40 grinding surface on one side thereof, a guard substantially enclosing the disc and having an opening through which a finger nail may 45 be brought in contact with said disc, and means for continuously rotating said disc comprising a shaft extending outside said 50 guard.

3. In a manicuring device, a rotatable shaft, a buffer wheel secured to said shaft, a grinding disc secured to said shaft against said wheel, and a guard enclosing said wheel 55 and disc, there being an opening in said guard to expose the buffing surface of said wheel and a second opening to expose the grinding surface of said disc.

4. In a manicuring device, a compound 60 grinding and buffing wheel having a grinding surface on one side and a buffing surface around the periphery, together with a guard having an opening through which a finger nail may be trimmed by the grinding surface and another opening through which a 65 trimmed nail may be polished by the buffing surface.

5. In a manicuring device, a hand piece, a 70 rotatable shaft projecting from said hand piece, an abrasive wheel secured to the end

of said shaft, a housing substantially enclosing the abrasive portion of said wheel, supporting means connecting said housing with said hand piece, and an opening in said housing through which a finger nail may be brought into working engagement with said wheel. 70

6. In a manicuring device, a hand piece, a rotatable shaft projecting from said hand piece, a disc secured to the end of said shaft, said disc having abrasive material forming a flat cutting surface on the side thereof remote from said hand piece, a housing substantially enclosing said disc, supporting means connecting said housing with said hand piece, and an opening in the end of said housing through which a finger nail may be brought into working engagement with said cutting surface. 75 80

In witness whereof, I hereunto subscribe my name this 4th day of November, A. D. 1929. 85
